(57) **CLAIM**

The ornamental design for a loop cap for a beverage container, as shown and described.

DESCRIPTION

FIG. 1 is a top perspective view of a loop cap for a beverage container showing my new design.

FIG. 2 is a front view thereof.

FIG. 3 is a rear view thereof.

FIG. 4 is a right side view thereof.

FIG. 5 is a left side view thereof.

FIG. 6 is a top plan view thereof.

FIG. 7 is a bottom plan view thereof; and,

FIG. 8 is bottom perspective view thereof.

(Continued)

The dot-dash lines represent the claim boundaries and form no part of the claimed design.

1 Claim, 8 Drawing Sheets
